SORTING TABLE PAD

Frederick W. Oxley, Clinton, and Robert L. Holmes, Naval Base, S. C., assignors to Raybestos-Manhattan, Inc., Passaic, N. J., a corporation of New Jersey

Application March 16, 1948, Serial No. 15,162

4 Claims. (Cl. 193—1)

1

The invention relates to a sorting table pad for automatic spoolers of the type employed for winding yarn from spinning bobbins to larger packages, known as "cheeses," for the purpose of combining a number of relatively short threads into a single long strand of yarn. In the operation of automatic spoolers of the Barber-Colman type, the empty bobbins and bobbins with yarn on that have broken down during running are ejected from their holders to a conveyor which deposits them on a sorting table at one end of the machine where the operator sorts out those having yarn thereon and puts them back in the bobbin holders to be tied again. The empty bobbins are dropped into trucks beneath the table, while those with badly tangled yarn or with too small an amount of yarn to be economically handled on the spooler, are sent to a smaller winding machine known as a tailings machine.

As the sorting tables provided on Barber-Colman spoolers are made of steel, the operators have followed the practice of placing linoleum, fiber board, cardboard, leather or artificial leather sheets onto the surface of the sorting table to protect the wooden bobbins against damage as they are ejected onto the table from the conveyor. It has been found that these sheets usually wear out rapidly at the point where the bobbins contact same in their fall from the conveyor. It has also been found that the bobbins tend to pile up on the sorting table between sorting operations, thereby causing bobbins being ejected to strike against bobbins in the accumulated pile, thus causing bobbin damage.

The present invention contemplates the provision of a pad adapted to be mounted upon the upper surface of a sorting table, the pad being preferably formed of rubber or rubber-bonded fibers to receive the wooden bobbins as they are ejected from the spooler conveyor.

This invention further contemplates the provision of a pad formed of resilient material and provided with a resilient rubber bumper which acts to disperse the wooden bobbins over the entire surface of the sorting table to prevent the formation of an accumulated pile.

This invention further contemplates the provision of a sorting table pad embodying a resilient base pad, a bounce pad, adapted to be adjustably positioned along the base pad and a bumper mounted on the bounce pad, the three members being secured in adjusted position by means of bolts extending upwardly through the base pad and bounce pad for threaded engagement in nuts embedded within the bumper.

This invention further contemplates the pro-

2

vision of a sorting table pad which is relatively simple and inexpensive to manufacture, which may readily be adjusted for use, and which will have a relatively long service life.

5 This invention embodies other novel features, details of construction and arrangement of parts which are hereinafter set forth in the specification and claims and illustrated in the accompanying drawing wherein:

10 Fig. 1 is a top plan view showing a pair of sorting table pads embodying features of this invention mounted upon a sorting table of the type employed with a Barber-Colman spooler.

Fig. 2 is a transverse sectional view taken along the line 2—2 of Fig. 1.

15 Fig. 3 is a side elevational view illustrating a sorting table pad.

Fig. 4 is a top plan view of same.

Fig. 5 is a sectional view taken along the line 5—5 of Fig. 3.

20 Fig. 6 is a fragmentary top plan view illustrating a modified form of this invention.

Fig. 7 is a sectional view taken along the line 7—7 of Fig. 6.

25 Fig. 8 is a sectional view, corresponding to Fig. 7, illustrating another modified form of this invention.

Fig. 9 is an end elevational view illustrating another modified form of this invention.

30 Referring now to the drawing for a better understanding of this invention, the sorting table pad 6 is adapted to be mounted upon the upper surface of a sorting table 7. The sorting table illustrated in the drawing is of a type employed with Barber-Colman spoolers and provided with two adjoining surfaces 8 and 9 which slope outwardly and downwardly from an apex 10 to receive wooden bobbins 4 falling by gravity from the discharge end of an endless conveyor which is shown in dotted outline at 5 in Fig. 1.

35 Referring now more particularly to Figs. 1 to 5, inclusive, in the drawings, the pad 6 is shown as comprising a base pad 11 which is preferably cut from a sheet of rubber or rubber-bonded fibers and of sufficient width and length to substantially

40 cover one of the inclined surfaces 8 or 9 of the sorting table. A bounce pad 12, preferably formed of resilient rubber, is provided on the upper surface of the base pad 11 and preferably disposed adjacent the apex 10 of the sorting table. A bumper pad 14 is provided on the upper surface of the bounce pad 12 and is preferably formed of relatively soft resilient rubber to readily absorb the shock of bobbins falling thereon from the conveyor 5.

45 The base pad 11 is shown formed with a pair

of parallel slots 16-16 to receive the shank portions of bolts 17. The bounce pad 12 is formed with a pair of apertures 18-18 disposed in registry with their respective slots 16-16 to also receive the shank portions of the bolts 17-17. A pair of nuts 19-19 are embedded within the bumper 14 to receive and engage the threaded ends of their respective bolts 17-17.

When the pad 6 is mounted for use upon a sorting table 7, the bounce pad 12 and the bumper 14 are adjustably positioned along the base pad 11 to dispose the bumper 14 in the path of bobbins being ejected and dropping by gravity from the conveyor 5 of the spooler. The resilient bumper 14 acts to yieldably absorb the shock set up by the falling bobbins and to disperse the bobbins in various directions over the surface of the base pad 11, thus preventing an accumulation of bobbins in the line of travel of subsequently ejected bobbins. During the operation of the spooler, it will be understood that some of the bobbins may first strike against the bounce pad 12 and thence against the bumper 14, or vice versa.

To reduce the cost of manufacture, the base pad 11, bounce pad 12 and bumper 14 are preferably cut from sheet material to provide individual parts as heretofore described in connection with Figs. 1 to 6 in the drawings. It will also be understood that it is not essential that these parts be formed from the same type of material. It is contemplated, however, that the bounce pad 12 and bumper 14 should be formed of a suitable resilient material, such as rubber or rubber composition, to prevent injury to the bobbins falling thereon.

Referring now more particularly to Figs. 6 and 7 in the drawing, the sorting table pad 20 is shown as comprising a base pad 21 having a bounce pad 22 secured thereto by means of bolts 23 and nuts 24, the latter being embedded within the bounce pad. The bounce pad 22 is formed with an integral bumper portion 26. The bounce pad 22 and bumper portion 26 are preferably formed from resilient material, such as rubber, while the base pad 21 may be formed from any suitable sheet material.

Fig. 8 illustrates a further modified form of this invention in which a sorting table pad 28 is formed as a single unit including a base portion 29, a bounce pad portion 31, and a bumper portion 32. It is contemplated that this type of pad could be formed from a suitable resilient material, such as rubber.

Fig. 9 illustrates another modified form of this invention in which the base pad 36 is formed wedge-shape as viewed in end elevation to cause the bobbins to roll downwardly toward the thin edge of the pad after striking against the bumper 37 positioned upon the bounce pad 38. The base pad 36, bumper 37 and bounce pad 38 may be formed as a single integral unit, or may be formed as separate individual units in the manner heretofore illustrated and described in connection with the other forms of this invention. The bumper 37 and bounce pad 38 are, however, formed of resilient material, such as rubber, to

absorb the shock due to bobbins falling thereon. In the use of this form of the invention, the pad may be mounted upon a sorting table having a flat horizontal top surface.

While this invention has been shown in several forms, it is obvious to those skilled in the art that it is not so limited but is susceptible of various changes and modifications without departing from the spirit and scope of the claimed invention.

We claim as our invention:

1. In a pad for use on sorting tables to prevent damage to bobbins being ejected from an automatic spooler, a base pad, a bounce pad provided on and extending upwardly from said base pad, said bounce pad being formed of resilient material and having a smaller top surface area than said base pad, a bumper provided on and extending upwardly from said bounce pad, said bumper being formed of resilient material and having a smaller top surface area than said bounce pad, said bumper being in the form of a ridge extending across the top surface of the bounce pad, said bounce pad being positioned intermediate the ends of said base pad and adjacent one side thereof.

2. In a pad for use on sorting tables to prevent damage to bobbins being ejected from an automatic spooler, a base pad, a bounce pad provided on and extending upwardly from said base pad, said bounce pad being formed of resilient material and having a smaller top surface area than said base pad, a bumper provided on and extending upwardly from said bounce pad, said bumper being formed of resilient material and having a smaller top surface area than said bounce pad, and means to adjust the position of said bounce pad relative to said base pad.

3. In a pad for use on sorting tables to prevent damage to bobbins being ejected from an automatic spooler, a base pad, a bounce pad provided on and extending upwardly from said base pad, said bounce pad being formed of resilient material and having a smaller top surface area than said base pad, a bumper provided on and extending upwardly from said bounce pad, said bumper being formed of resilient material and having a smaller top surface area than said bounce pad, said base pad, bounce pad and bumper being in the form of a single integral unit.

4. In a pad for use on sorting tables to prevent damage to bobbins being ejected from an automatic spooler, a base pad, a bounce pad provided on and extending upwardly from said base pad, said bounce pad being formed of resilient material and having a smaller top surface area than said base pad, a bumper provided on and extending upwardly from said bounce pad, said bumper being formed of resilient material and having a smaller top surface area than said bounce pad, said base pad being wedge-shaped as viewed in end elevation.
